UNITED STATES PATENT OFFICE

2,168,982

COLLAPSIBLE BED

Bennie McKeithan Graham, Tupelo, Miss.

Application September 9, 1937, Serial No. 163,147

2 Claims. (Cl. 5—154)

The invention relates to a bed or the like and more especially to collapsible or foldable beds. The primary object of the invention is the provision of a bed of this character, wherein a sectional case creates the head and foot pieces to the bed and when these sections are together the bed is folded and its mattress carrier concealed from view, being enveloped or incased, thus the bed in this condition occupies a minimum space 10 within a room or other enclosure thus such bed is adaptable for service in congested quarters, for example, in apartment houses or other edifices.

Another object of the invention is the provision of a bed of this character, wherein the mattress 15 together with the bed clothing or coverings can be concurrently-folded and confined within the case and in this manner the bed with its adjuncts being together, the said bed being readily operated for the extending thereof from collapsed folded condition for occupancy and is possessed of sturdiness and continuity of use.

A still further object of the invention is the provision of a bed of this character, wherein the same involves refinements over the subject matter of an application for United States Letters Patent filed August 7, 1935, and serially numbered 35,176.

A still further object of the invention is the provision of a bed of this character, which is simple in its construction, thoroughly reliable and efficient in operation, readily and easily folded or unfolded, neat in appearance and imitative of a wardrobe or other like article of furniture when in its folded condition, occupying the least possible space when not in use, assuring comfort to a user, and inexpensive to manufacture.

With these and other objects in view, the invention consists in the features of construction, combination and arrangement of parts as will be hereinafter more fully described, illustrated in the accompanying drawings, which disclose the preferred and modified forms of embodiment of the invention and pointed out in the claims hereunto appended.

In the accompanying drawings:

Figure 1 is a vertical longitudinal sectional view of a bed constructed in accordance with the invention and in extended or unfolded condition supporting its mattress.

Figure 2 is a fragmentary side elevation partly diagrammatic showing the bed in a partially folded condition.

Figure 3 is a vertical sectional view of the bed 55 folded.

Figure 4 is a top plan view partly in section when the bed is unfolded.

Figure 5 is a detail enlarged sectional view taken on the line 5—5 of Figure 4 looking in the direction of the arrows.

Figure 6 is an enlarged detail sectional view taken on the line 6—6 of Figure 4 looking in the direction of the arrow.

Figure 7 is a fragmentary perspective view of the mattress for the bed partly folded.

Figure 8 is a fragmentary vertical longitudinal sectional view through a slightly modified form of bed.

Figure 9 is a sectional view on the line 9—9 of Figure 2.

Similar reference characters indicate corresponding parts throughout the several views in the drawings.

Referring to the drawings in detail, particularly Figures 1 to 7 and 9 inclusive, the bed constituting the present invention is of a collapsible or foldable type and A designates generally the case formed in two sections 10 and 11, respectively, for matching relation to each other and the section 10 constitutes the head piece while the section 11 at the upper portion thereof is cut into for a front cover piece 12 being hinged at 13 to the section 10 at the top thereof giving access to the interior of the case when the sections 10 and 11 are together. The cover section 12 swings vertically to opening and closing positions and by reason of its shape when in closed position with the sections 10 and 11 together functions in holding such sections in this position. The section 10 at its base carries a resilient tread 14 while in suitable clearances in the base of the section 11 are located rollers 15 being journaled at 16 so that this section 11 when pulled outwardly away from the section 10, 40 the said rollers 15 traction a foundation or flooring thereby assuring easy folding or unfolding of the bed while the section 10 through the tread 14 is held stationary.

Arranged between the sections 10 and 11 is a 45 mattress spring or carrier involving a pair of open frames 17 and 18, respectively, these being similar to each other and at their outer side rails 19 have in association therewith hinge joints 20 swingingly connecting the frames 17 and 18 50 together intermediate of the bed. These open frames have spring-tensioned fabric coverings 21 so that a mattress will be supported thereon against sagging and for service.

Arranged on opposite sides of the frames 17 55

and 18 and fitted interiorly of the sections 10 and 11 at the upper portions thereof are perpendicularly arranged elongated slotted guides 22 while fixed to the bases of the sections 10 and 11 interiorly of the latter are bearings 23 and shiftably and pivotally engaged in the guides 22 and pivoted to the said bearings 23 at 24 and 25, respectively, are the operating end levers 26 and 27, respectively, of lazy tongs 28, one of the latter being at each side of the bed, the levers 26 being hinged together at 29 while the levers 27 are hinged together by the hinge joints 20 connecting the frames 17 and 18 together and on the extending and contracting of the lazy tongs 28 the sections 10 and 11 are moved apart and brought together while concurrently unfolding and folding with said tongs are the frames 17 and 18 with respect to each other.

At the hinge joint points 30 of the lazy tongs 28 are pivotally supported lifter arms 31, these having the curved contact terminals 32 and are provided with elongated slots 33 for accommodating guide studs 34 carried by the levers 27 and the purpose of the arms 31 is for the lifting of the frames 17 and 18 when in unfolded condition to a horizontal plane in alignment with each other and in this manner the mattress 35 is held for occupancy, the bed being extended from collapsed condition.

30 The mattress 35 is of a two-part build and carries zipper fasteners 36 at opposite sides thereof and at the meeting ends of the two parts thereof and these zipper fasteners singly afford a fold line and a hinge connection between the parts at 35 opposite sides, being understood, of course, that when one zipper fastener is closed, the other zipper fastener is open thus the closed zipper fastener functioning as a hinge for the folding of the mattress concurrently with the folding of the frames 17 and 18 when carrying said mattress.

The base of the section 10 interiorly of the latter at the center thereof is fitted with a latch guide 37 for a latch 38 carried by the section 11 so that the said latch 38 will be directed into 45 a keeper notch 39 in the section 10 on the bringing together of the sections 10 and 11 and thus fastening the same in this condition. The latch involves a tensioning spring 39' and a releasing rod or plunger 40 readily accessible at the cover 50 12 opening in said section 11 so that the latch can be manually released when it is desired to extend the bed for use.

The contacts 32 of the arms 31 play in seats 41 provided in the lower edge of the side rails 55 of the frames 17 and 18 during folding and unfolding activity thereof.

At the hinged joints 20 is the depending hanger 42 through which are laced crossed cables 43 60 diagonally disposed beneath the frames 17 and 18 and having their ends anchored at 44 to the sections 10 and 11 next to opposite sides thereof, these being lateral truss cables built into the bed and become slackened on the folding of the bed 65 and taut on the unfolding thereof. This hanger

42 serves as a brace between the spring frames 17 and 18.

In Figure 8 of the drawings there is shown a slight modification of the bed, wherein the levers 45, which are similar acting to the levers 27, have 5 associated therewith the lifter arms 46, these being pivoted at 47 directly to the frames 48, which are similar to the frames 17 and 18, and such arms 46 are pivoted at 49 to levers 50, these being pivoted at the hinges 51 for the levers 45 10 and also slidably and pivotally fit at 52 in slotted hanger links 53 which at 54 are pivoted to the hinge between the frames 48 and the hinge joint between the levers 45. The levers 46 are slotted at 55 for the pivots 57 in the levers 45 so that 15 the frames 48 and the said levers 45 will approach each other on the folding of the bed.

The cover 12 when in open position rests upon the top of the section 10 of the bed as is clearly shown in Figure 1 of the drawings. 20

The hanger 42 carries clips 55 for the cables 43.

It is, of course, understood that the bed may be made of any desirable material and different sizes and widths.

What is claimed is:

1. A collapsible bed comprising a case having separable enclosing sections constituting head and foot pieces, lazy tongs between and at opposite sides of the sections and having end levers pivotally and slidably connected to said pieces, 30 respectively, and extended and contracted by movement of said pieces, a foldable mattress carrier having hingedly connected sections supported by said lazy tongs, the hinge connection of the sections being pivoted to the lazy tongs intermediate of the extent thereof, and lifter arms pivotally and slidably linked with said lazy tongs and arranged at opposite sides of the pivotal connection of the sections of the mattress carrier with the lazy tongs and active on the sections of said 40 mattress carrier for supporting the said sections in a horizontal plane in alignment with each other when the said lazy tongs are extended.

2. A collapsible bed comprising a case having separable enclosing sections constituting head and 45 foot pieces, lazy tongs between and at opposite sides of the sections and having end levers pivotally and slidably connected to said pieces, respectively, and extended and contracted by movement of said pieces, a foldable mattress carrier 50 having hingedly connected sections supported by said lazy tongs, the hinge connection of the sections being pivoted to the lazy tongs intermediate of the extent thereof, lifter arms pivotally and slidably linked with said lazy tongs and arranged 55 at opposite sides of the pivotal connection of the sections of the mattress carrier with the lazy tongs and active on the sections of said mattress carrier for supporting the said sections in a horizontal plane in alignment with each other when 60 the said lazy tongs are extended, said lifter arms being provided with elongated slots, and guide studs on said lazy tongs and accommodated in said slots.

BENNIE McKEITHAN GRAHAM. 65
